WELL SCREEN AND PERFORATION
CLEANER

Wilson Tarkington, Dallas, Tex.

Application August 1, 1944, Serial No. 547,528

4 Claims. (Cl. 166—20)

1

My invention relates to well screen and perforation cleaners utilizing the hydrostatic pressure in an oil well to effect the clearing of mud and other debris from the slots and perforations in well screens and the like, said screens usually located adjacent the producing formations in wells. Such perforated sections of well screens are usually seated on the bottom of the well and extend upwardly telescopically into the "water string" of oil well casing. Frequently the uppermost end of the liner is provided with a fixed packer to form a seal with the wall of the casing in which it is seated so as to exclude mud, shale, sand and the like from the bore of the well. In certain instances the screen joints are interspersed with casing joints, having no perforations. The bottommost section of the liner is sealed by various means, usually a back pressure valve, to prevent the entrance of sand, shale, etc., at the bottom.

Screen and perforation cleaners of the hydrostatic type heretofore used, operable by means of a hoist and cable, usually are provided with a packing means to form a seal between the cleaner and the perforated liner wall, a low pressure chamber above the packing means opening to the well pressure below the packing means, provided with valvular means for exposing the low pressure chamber to the well pressure, thereby causing a low pressure area to be formed within the annular isolated section of screen below the packer.

The primary object of my invention is to provide a screen and perforation cleaner, having a telescopic sleeve valve connected between a low pressure chamber above the valve and a load receiving chamber below the valve, having identically the same construction, in so far as valvular control is concerned, as the bailer patented to me in Patent No. 2,198,490, dated April 23, 1940, except that the bottom of the bailer shoe is threaded for connection to it of a combined packer and seating device described herein. The cleaner is provided with means for seating the tool at a predetermined zone in the well screen and for the simultaneous opening of the sleeve valve to communicate the well pressure to the low pressure chamber, thereby radially expanding the packers tightly against the wall of the screen and drawing a charge into the load receiving chamber through the isolated section of perforations. When the charge is drawn, the low pressure chamber is equalized with the fluid pressure in the well, thereby permitting the packers to disengage themselves.

2

One other object is to provide automatically operable hydraulic means for seating the tool at a predetermined depth in the well fluid by closing a hydraulically operable valve located in the combined packer and seating device, by "spudding" the tool (two or three feet), and also means for the automatic release of the packers from the liner wall, when the low pressure chamber is filled, and means for withdrawal of the tool easily without consequent disrupting of the rubber packers on the burrs usually projecting into a liner.

One further object is to provide an improved cleaner whereby the hydrostatic bailer mentioned herein may be quickly transformed into a cleaner by simply connecting the combined packer and seating device to the bottom valve of the bailer. Another object of the invention is to relieve the operating cable from as much stress as possible, by opening the tool by a downward movement. Should a second downward movement be actuated by the descending fluid head when the low pressure chamber is opened, the automatically closable valve means will act to check such movement.

This cleaner is also effective by eliminating the topmost packer from the mandrel. The bottommost packer is essential in seating the device. In this operation, the descending fluid column is unobstructed, until it meets with resistance at the bottom packer which forms a seat, in combination with the closed valve contained therein. This operation drives the fluid outwardly through the perforations, opening perforations where they are not too tightly clogged.

Further objects appear herein:

Referring more particularly to the drawings: Fig. 1 shows an elevational side view of applicant's well screen and perforation cleaner. Fig. 2 is a partial sectional side view of 2—2 shown at Fig. 1. Figure 3 is a partial sectional side view of that part of Fig. 1 indicated at 3—3. Fig. 4 is a sectional side view of a part of Fig. 1 indicated by 4—4 at Fig. 1. Fig. 5 is a sectional view of Fig. 4 taken at 5—5 of Fig. 4. Fig. 6 is a sectional view taken at 6—6 of Fig. 4. Fig. 7 is an enlarged sectional view showing detail of the valve generally indicated at 7—7 of Fig. 2. Fig. 8 is a view taken at section 8—8 of Fig. 7. Fig. 9 is an enlarged view of part of top 9—9 of Fig. 2 showing construction of an auxiliary dumping valve.

Fig. 2, Fig. 3, and Fig. 4, show the general combination in sectional view in its regular assembly. Fig. 4 shows the combined packer and

seating device normally positioned in a usual section of well screen. Section 9—9 of Fig. 2 illustrates a closed top adapted for cable (not shown) connection, with means for relieving excess pressure while withdrawing the tool from a well. A low pressure chamber 10 may be constructed from one or more lengths of tubular material and may be of varying lengths, dependent on the height of the well derrick. A telescopic sleeve valve is attached to the bottommost end of low pressure chamber 10, the valve more generally indicated at 7—7 at Fig. 2, while depending therefrom is a load receiving chamber 30 of a suitable length (usually the length of the low pressure chamber 10), provided with a connection for a bottom bailer valve 36 (Fig. 3), threaded at 44 to receive the top connection of the combined packer and seating device shown in detail at Fig. 4. Located in the top 9—9 of Fig. 2 is a threaded nipple 9 supporting a seat for a co-operating ball valve 7 urged into compression for various relief pressures by means of a helical spring 3, a disc 5, and a set screw 2. An opening 4 is for fluid pressure escape. The ball valve urged by spring tension acts to oppose all well pressure while the tool is being lowered into the fluid to the zone of operation, and to retain fluid in the tool at a predetermined pressure in the pressure chamber on elevation of the tool. Attached to low pressure chamber 10, preferably threadedly connected thereto at 10—a is the sleeve valve inner cylindrical member or element 11, shown in more detail at Fig. 7. The lower end of the sleeve valve outer cylindrical element 12 is threadedly attached to top of load chamber 30 at 30—a. The valve comprises outer and inner concentric cylindrical elements. Inner cylindrical element 11 telescopes into outer cylindrical element 12, the flanged shoulder 15 formed on element 11, being limited in longitudinal movement by abutments at 80 and 16—a respectively on the element 12. On the lowermost end portion of element 11, an inner valve member 78 with valve ports (Fig. 7), 21, 22 and 23 therein is formed. The limited reciprocal movement of element 11 within element 12 is adapted to reciprocally alternatively open and close port 14 in element 12 to act as a closure for port 14. An intermediate sleeve valve member 17 is mounted in outer cylindrical element 12 below port 14 and inner cylindrical member 78 is slidably movable within the intermediate sleeve valve member 17. Ports 21, 22 and 23 in the inner sleeve valve member on the lowermost end portion of element 11 are adapted to register with ports 83, 84 and 85 in the intermediate sleeve valve member 17 when the cylindrical element 11 actuated by the chamber 10 is telescoped within outer cylindrical element 12 to open the valve (Fig. 2), but when the valve parts 11 and 12 are in their extended relation, valve ports 21, 22 and 23 are closed (Fig. 7), being moved into the imperforate upper portion of the intermediate sleeve 17. Ports 21, 22 and 23 are held in longitudinal alignment with ports 83, 84 and 85 by means of a key 79 and a co-operating keyway 79—a formed on the elements 11 and 12 respectively. A set screw 86 extends through element 12 toward the port 85 in sleeve 17 to hold the sleeve against rotation. Intermediate valve member 17 engages packing gasket 16 and the downwardly facing abutment formed in element 12 at 16—a. The lowermost end of 17 is seated concentrically upon the uppermost end of load chamber 30 threaded into the element 12 at 30—a. The inside diameter of 30 is slightly

smaller (Fig. 8) than the outside diameter of member 17. Casing 30 is threaded into element 12 and threaded upwardly to firmly engage and hold the sleeve 17 within the element 12. The intermediate valve member 17 is provided with exterior longitudinal conduits 19 to permit passage of fluid from the load receiving chamber 30 upwardly through the open ports of the valve and into the low pressure chamber 10. Intermediate valve member 17 has a vertical fluid passage 18 communicating its lowermost end with the port conduit 19 and opening outwardly at the upper end of the member 17 to communicate with port 14 in the outer cylindrical element 12. The upper portion of fluid passage 18 is enlarged and in this enlarged portion is a ball valve seat at the lower end thereof. Ball valve 82 is adapted to rest on the valve seat and the helical spring 81 above the ball valve urges the ball valve into closed position, preventing downward flow of fluid through the passage 18, but when the valve ports 21, 22 and 23 are in their closed position, fluid may pass upwardly through the passage 18 and outwardly through the port 14 to reduce any excessive pressure within the load receiving chamber. The lower end of element 11, to form an inside valve member 78, is provided with solid type packing rings 20 and 24. Packing ring 20 is followed by close-fitting metal sleeve 25, having four ports adapted to align with ports formed on the inside inner valve member 78 and held against rotation by slot and pin 88, a packing ring 24 follows 25 and a close fitting metal sleeve 26 extends slightly past the lowermost part of 18 to permit packing adjustment. A metal disc 27 with opening for stud, following 26, and a stud with retaining nut 29 screwed into the lowermost part of 78 provide an adjustment for the packings.

In operation, when the valve contacts fluid while descending in a well, the action of the fluid pressure against the disc 27 urges both metal sleeves and packing rings upwardly, operating to expand both packing rings against the inside wall of intermediate valve member 17 and the outer surface of the inside valve member 78, insuring a perfect seal against fluid entering the low pressure chamber while submergence is taking place. As the cleaner emerges from the fluid, the confined high pressure trapped in the low pressure chamber 10 acts to distend the packings 20 and 24 from the ports 21, 22 and 23, thereby reserving a pressure in the pressure chamber gauged by tension on the spring-pressed ball valve seated in the top 1 (Fig. 2).

A bailer bottom valve is threadedly attached to load receiving chamber 30 (Fig. 3). The valve comprises a shoe 37 with sleeve 36 threadedly connected thereto and having an opening 39—a in one side. Shoe 37 has an opening 38 adapted to register with opening 39—a in the sleeve 36. Removable combined partition and seat 41 is seated within shoe 37 and carries a one-way flap-valve 40 for retaining the load in the load receiving chamber 30. Openings are brought into registry by well known manually operable means by rotating the sleeve 36 relative to the shoe 37 until opening 39—a is in alignment with opening 38. Shoe 37 is threaded at its lowermost end 44 for connection to the topmost end of a combined packer and seating device shown at Fig. 4.

The combined packer and seating device comprises a tubular mandrel 47 with circumferential shoulders 51 and 59 thereon for seating spaced packers 52 and 57. An inner tubular member

47—a is welded therein at 76 and 55. Inner tubular member 47—a to form a by-pass duct is provided with slots 72, 74 and 56 longitudinally formed on the outside thereof, said slots terminating and cooperating with the ports 50 and 50—a. The purpose of these by-pass slots is herein shown. Substantially mounted on the outside of the mandrel 47 are rubber packing elements 52 and 57. The upper packing element 52 as well as the lower packing element 57, are commonly known as swab cups and are well adapted to this service. Packing element 52 is seated in the usual position (flexible end upwardly), on metal thimble 53 supported on the shoulder 91. Packing element 57 forms an opposing packer as well as a seating element, and is held firmly in an inverted position (flexible end downwardly), on metal thimble 58 firmly against the shoulder 59. Both packers are firmly seated in thimbles 53 and 58 by means of screw thread pressure of pipe couplings 66 and 68 urged against cylindrical rings 60—a and 60—b respectively. The cylindrical ring 60—a is provided with ports 50 and 50—a cooperating with ports in mandrel 47, communicating with the slots 72, 74 and 56 formed in the inner tubular member 47—a to permit the by-passage of fluid through the mandrel 47. The port 73 in 47—a with a corresponding port in 47 are formed in the inner tubular member 47—a and mandrel 47 respectively. Port 55 is of slightly larger dimensions than port 73 to afford a welding face for sealing the tubular parts together. Inner tubular member 47—a fits snugly within mandrel 47 as shown at Figs. 4 and 5. Inner tubular member 47—a, to form a one-way inlet passageway from port 55 to the bailer bottom, is sealed at its lowermost end 75. The assembled parts 47 and 47—a may now be considered as an integral member with the interior of part 47—a providing the main bore of the mandrel. A back-pressure valve comprising a body 61, a seat 63, a ball valve 66 and a cooperating cage is threadedly attached into pipe coupling 60. The seat, ball and cage are well known in the art of well pumping, but in this instance are placed in an inverted position for reasons herein explained. A pipe coupling 67 and a plug 68 with ample fluid passage perforations 70, are threadedly attached to the lowermost end of the valve body 61. The device (Fig. 4) is thus provided ample fluid by-passage through the cage 64, the valve seat 63 (the steel valve ball 66 normally remaining apart from its seat 63, dependent on the lowering speed), upwardly through the valve body 61, and through the slots 72 and 56 and into the well fluid head through ports 50 and 50—a while the combination is descending in a well screen or liner having a fluid head, but the entry of any hydrostatic well pressure into the low pressure chamber will be through the port 55 located between the opposing packers. Thus, the screen and perforation cleaner shown at Fig. 1 can be moved with reasonable speed upwardly and downwardly within a well casing or liner containing fluid where the packers 52 and 57 are of a slidable fit. It will be understood that the opposing ends of the packers are of a very flexible nature and easily expanded. Their extreme radial diameter is somewhat less when not expanded, than that of the inside diameter of the perforated well screen 51 (Fig. 6), which shows a sectional view taken at 6—6 Fig. 4. They are also much less in diameter than the well casing above the screen, which permits the tool to descend rapidly through the fluid. When the

momentum of the tool is reduced above the mouth of the screen, the ball valve assumes its normal position (removed from its seat).

In operation, the screen and perforation cleaner is lowered into a well containing fluid by means of a cable and hoist (not shown) attached to top 1, and operable by hoist (not shown). The low pressure chamber 10 has considerable weight, even while submerged in fluid. On elevation of the cleaner to lower into a well the sleeve valve shown at Fig. 2, assumes its normally closed position as shown at Fig. 7, by means of the suspended weight of the loading chamber shown at Fig. 3 and the combined packer and seating device shown at Fig. 4, the ports in the inner sleeve valve member 18 being drawn upwardly into the imperforate portion of the intermediate sleeve valve member 17. Since the screen or liner to be cleaned occupies only a small per centum of the bottom portion of the lineal depth of the well, the cleaner may be lowered rapidly without interference or accidental opening of the sleeve valve Fig. 7, until the cleaner approaches the top of the liner or reduced diametrical section of the well when the speed of the lowering cable is reduced to a slow rate by the operator controlling the hoist. When the zone of operation is reached, the tool is stopped by the operator for an instant. Therefore at the zone of operation the tool is permitted to drop rapidly for several feet. This action, (the resistant fluid to the downwardly facing packer) thrusts the valve ball 66 against its seat 63, when urged by the dynamic rush of fluid upwardly through the seat 63, resulting in a sudden stoppage of the packer 57 on the fluid below the packer. This stoppage is sufficient to cause immediate telescoping of the sleeve valve elements 11 and 12 (Fig. 2) with consequent opening of the sleeve valve ports, establishing communication of the hydrostatic fluid pressure to the low pressure chamber above the sleeve valve. Since the openings to the low pressure chamber are through the port 55 and through the registered sleeve valve ports, a low pressure zone is established between the packers 52 and 57, and the hydrostatic pressure above the packer 52 and below the packer 57 acts to expand both the packers tightly radially against the inside wall of the perforated liner 51 until the atmospheric pressure in chamber 10 is equalized with the well pressure. When the low pressure chamber 10 is thus equalized with that of the well fluid head, packers 52 and 57 automatically break their sealing contact with the liner wall 51, and the tool can now be easily withdrawn from the well for unloading. In emerging the excess pressure in chamber 10 will find relief through seat 1. On elevation, valve parts 11 and 12 re-assume their normally closed position. The loading chamber 10 containing the debris recovered from the operation is unloaded through the registered openings 38 and 39 (Fig. 3) of the bottom bailer valve, which are brought into alignment by well known manually operated means. The retained pressure in chamber 10 will act to expel the load.

When the pressure in chamber 10 is exhausted or reduced through the loading chamber, there will yet remain in the pressure chamber an amount of fluid. An auxiliary valve located in the top 1 and in a bore 94 spaced apart from the main bore of the relief valve hastens the drainage of the remaining fluid. Fig. 9 shows a partial sectional view of the top, and the valve is generally indicated by the numerals 90 to 94 inclusive. Longitudinal bore 91 intersects lateral opening 94 communicating the pressure chamber

10 to atmospheric pressure. Threaded cylindrical element 98 has an upwardly extending tubular portion smaller diametrically than the bore 91, sufficient to permit compression of a helical spring 93 around the tubular part. A ball valve 92 is shown in its normal position, urged by spring pressure against an outer seat formed at the upper part of the bore 91. The topmost of the cylindrical element 98 has a cooperating inner seat for the ball 92. The spring is calibrated to yield slightly to atmospheric pressure from without the tool against the ball valve when a differential occurs in unloading. But the ball will quickly engage the seat at upper end of element 98, when the cleaner is submerging in fluid. When the low pressure chamber 10 is equalized with the well pressure at the bottom of the well, the ball moves upwardly to its outer seat or normal position to trap the pressure in the chamber. The auxiliary valve is automatically operable; to close the pressure chamber to the fluid while submerging, to confine the trapped pressure in the chamber while emerging, and to admit atmospheric pressure to the pressure chamber when a vacuum is formed during the unloading process. The amount of fluid entering the pressure chamber in submergence is negligible.

What I claim is:

1. In a screen and perforation cleaner for oil wells, a low pressure chamber with a one-way inwardly opening valve for retaining a load in said chamber, a threaded connection on said one-way valve connecting it with a combined packer and seating device, said packer and seating device comprising a hollow mandrel with opposing packers mounted thereon with means for bypassing of well fluid, said means comprising longitudinally formed ducts in the mandrel, the terminals of the ducts opening outwardly of the mandrel at a point above the topmost packer and at a point outwardly from the mandrel below the bottommost packer, an outward opening in said mandrel communicating with the main bore of said mandrel connected to the load retaining valve, said opening positioned between the packers and independent of the ducts, means for seating the packer and opening the low pressure chamber to the well pressure, comprising a seat and ball valve, a cage to support said ball independent of the seat while submergence is taking place at normal speed, said device being arranged to be suddenly dropped a short distance to close said ball valve and open said load retaining valve to well pressure while submerged in the well.

2. In a screen and perforation cleaning device for oil wells having fluid head, a tubular vacuum chamber threadedly connected to the upper end of the cleaning device, means on the tubular vacuum chamber for retaining said vacuum until the device is seated within the well screen, said cleaning device comprising a hollow mandrel, with opposing packers mounted on the ends thereof, said mandrel provided with ducts terminating outward of the mandrel above and below both packers, said ducts independent of the main bore in said mandrel, said main bore opening outwardly from the mandrel between the packers and communicating upwardly to the vacuum chamber, valvular means positioned at the lower entrance

of said ducts comprising a seat, inverted cage, and an upwardly closing valve ball, operating to close hydraulically at a predetermined point in the screen to seat the device, and to expand the packings mounting the device against the inner screen wall until a charge is taken through the openings in said screen.

3. In a screen and perforation cleaning attachment for connection to the lower end of an oil well bailer operable by vacuum means under pressure, said attachment comprising a hollow mandrel having a down-facing swab cup mounted on the lower end thereof, said mandrel provided with ducts terminating outwardly of the mandrel at the ends of said mandrel above and below said swab cup, said ducts independent of the main bore in said mandrel, said main bore opening outwardly above said swab cup and arranged to communicate with the vacuum chamber in said bailer above, valvular means connected to the mandrel ducts comprising a seat, an inverted cage supporting a valve ball when the valve is in its normally open position, said ball valve being arranged to seat upwardly upon the seat to close the ducts and seat the cleaning attachment by hydraulic pressure and to take a charge into the bailer above and to disengage the liner walls after receiving said charge.

4. In a screen and perforation cleaning device 30 for connection to an oil well cleaning tool having a low pressure chamber, a seating and packing device comprising a hollow mandrel with opposing packing elements spaced apart thereon operating to isolate a perforated section of casing, 35 fluid ducts formed longitudinally in said mandrel terminating outwardly from the mandrel above and below the packers, an outward opening in the mandrel between the opposing packers and terminating in main bore in the mandrel arranged 40 to communicate with the low pressure chamber attached to the upper end of the device, said opening independent of said fluid ducts, a normally open but hydraulically closable valve positioned within the ducts of the mandrel, said valve 45 operating to remain in a normally open position when the tool is passing downwardly through fluid at a normal speed, and movable upwardly to close said ducts against upward fluid flow when the tool is permitted to suddenly drop rapidly into 50 the liner at a predetermined point, radially expanding the downfacing packer against the screen wall to effect stoppage of the tool and to open the low pressure chamber and to hydraulically engage both packers to the screen wall 55 when a charge is being taken into the tool.

WILSON TARKINGTON.
